(57) **CLAIM**

The ornamental design for an anvil, as shown and described.

DESCRIPTION

FIG. 1 is a perspective view of an anvil.

FIG. 2 is a top plan view of the anvil of FIG. 1.

FIG. 3 is a bottom plan view of the anvil of FIG. 1.

FIG. 4 is a left elevation view of the anvil of FIG. 1.

FIG. 5 is a right elevation view of the anvil of FIG. 1.

FIG. 6 is a front elevation view of the anvil of FIG. 1; and, FIG. 7 is a rear elevation view of the anvil of FIG. 1.

The broken lines immediately adjacent the shaded areas represent the bounds of the claimed design while other broken lines are directed to environment and are for illustrative purposes only; the broken lines form no part of the claimed design.

1 Claim, 5 Drawing Sheets
